UNITED STATES PATENT OFFICE.

CEZAIRE JOLY, OF SALEM, MASSACHUSETTS.

AUTOMATIC TRAIN-STOPPING MECHANISM.

1,224,932.

Specification of Letters Patent.

Patented May 8, 1917.

Application filed July 13, 1914. Serial No. 850,812.

To all whom it may concern:

Be it known that I, CEZAIRE JOLY, a subject of the King of Great Britain, residing at Salem, in the county of Essex and State 5 of Massachusetts, have invented certain new and useful Improvements in Automatic Train-Stopping Mechanism, of which the following is a specification.

The essence of the present invention lies 10 in the provision of tripping mechanism disposed adjacent the road-bed of a railway and adapted to coöperate with a relief valve or train control device carried by the rolling stock, by means of which pressure in the 15 train pipe is relieved for automatically applying the brakes, such release being accomplished in a gradual manner to insure against sudden stoppage of the train and consequent likelihood of injury to the train 20 mechanism or its passengers. To this end I provide a series of tripping members arranged at suitable intervals from each other and manually operable to be positioned in the path of a relief valve on a train, said 25 25 valve being progressively opened to its fullest extent by contact with the spaced tripping members whereby to cause the application of the brakes slowly and automatically in the event the engineer of the train fails 30 to see or attempts to pass a stop signal simultaneously set upon operation of the tripping members aforesaid.

A further object in view is the provision 35 of tension means for the tripping members of my device when in their normal position through the instrumentality of which said tripping members will automatically assume an operative position for coöperation with the train valve should breakage occur in the 40 operating connection for said tripping members.

These and such other objects as may hereinafter appear are attained by the novel construction, combination, and arrangement 45 of parts to be hereinafter specifically described and claimed. Reference will now be had to the accompanying drawings forming a part of this specification, wherein:

Figure 1 is a side elevation of my stopping 50 mechanism showing more particularly the coöperation with the relief valve on the rolling stock with the tripping members of my device.

Fig. 2 is a top plan view.

Fig. 3 is a fragmentary plan view on an 55 enlarged scale of one of the tripping members.

Fig. 4 is a vertical sectional view on the line 4—4 of Fig. 3.

Fig. 5 is a sectional view taken about on 60 the line 5—5 of Fig. 3.

Fig. 6 is a side elevation of a semaphore or signal member coöoperating with the tripping mechanism and

Fig. 7 is a plan view of a slightly modified 65 form of the device.

Referring to the drawings the numeral 1 designates a relief valve which is connected to the train pipe 2 of a train and by means of which valve pressure in the train pipe 70 may be relieved for the application of the air brakes. This valve is so arranged as to coöperate with certain tripping mechanism disposed adjacent the track and designed to operate said valve by contact therewith 75 to open the valve and thereby relieve the train pipe pressure in the manner hereinbefore suggested.

The tripping mechanism comprises a plurality of tripping members 3 arranged upon 80 suitable rests or plates 4 which may be connected to the railway ties or otherwise secured in proper position as most clearly shown in Fig. 2 of the drawings. These tripping members are pivotally secured to 85 the plates 4 as indicated at 5 so as to swing in a horizontal plane when actuated by the connecting rod 6 which is connected to all of said members at one end of the latter so as to operate the same simultaneously. 90 These tripping members are each formed with a contact arm 3' extending vertically and adapted to lie in the path taken by the relief valve 1 when said arms are swung into an operative position shown in full lines 95 in Figs. 1 and 2 by means of a lever 7 connected to the operating rod 6 through a link 8. This lever 7 may be located in the usual tower or at a suitable point for operation of the train stopping mechanism comprehended by this invention. A semaphore or signal 100 9 supported on the post 10 is interposed between the lever 7 and the tripping members, said semaphore being operatively connected to said lever through the bell crank levers 11, 12 and the connecting rods 13, 14 and 15. It will thus be obvious that 105 in the use of the device when the lever 7 is

operated through the connecting rods hereinbefore mentioned the tripping members and the semaphore or signal will be simultaneously operated so as to assume positions 5 wherein the former will lie in the path of movement of the valve 1 and the latter in a horizontal position as a stop signal to be observed by the engineer of the train. As shown most clearly in Fig. 1 of the drawings 10 the contact arms 3' are of varying heights, increasing in height in the direction of movement of the train, the upper extremities of said arms being preferably beveled, so that should the engineer attempt to 15 pass the stop signal, the valve 1 will successively contact with the contact arms and progressively open said valve until it is opened its full extent. In this manner the 20 valve is opened gradually and the train brought to a gradual rather than to a sudden stop which would be likely to cause injury to the brake mechanisms of the train or to the passengers of the same.

Arranged to coöperate with each of the 25 tripping members 3 is an expansion spring 16 disposed upon a guide rod 17 connected in any desired manner to the pivotal connection of the operating rod with each tripping member. The purpose of these springs 30 is to place the tripping mechanism under tension when the tripping members are swung into their normal position out of co-operative relation with the valve 1, and as most clearly shown in Fig. 3 of the drawing. 35 Thus when the lever 7 is unlocked or released the tendency of these springs 16 is to expand and to move the tripping members into the operative position shown in full lines in Fig. 2. Hence if a break occurs in 40 the rod 6 or at any point intermediate the tripping members and the lever 7 which holds said tripping members in the inoperative position, the springs will cause said members to assume their operative relation 45 to the valve 1 so as to stop the train in the manner hereinbefore described, irrespective of the position of the semaphore. I also contemplate the utilization of a fusible connection 17' in the rod 13 so that when the 50 mechanism of this invention is located upon a bridge, for instance, and said bridge is burned, the tripping mechanism will be released and under actuation of the springs the tripping members will be brought into a 55 position for automatically stopping the approaching train.

In Fig. 7 is shown a slightly modified form of the invention in which the numeral 3^a designates a plurality or a series of tripping members having the contact arms 3^b bent upwardly therefrom and said tripping members are pivotally disposed in a manner for swinging in a horizontal plane as described with reference to the preferred form. 60 The operating rod 6^a leading from an oper-

ating lever in one direction is connected at one extremity with a bell crank 6^b which is also connected by a link 6^c to the first tripping member. The succeeding members are connected by similar links 6^d and 6^e so as to simultaneously operate the tripping members upon actuation of the operating rod 6^a. In this modified form the springs are preferably not utilized. 70

It will be obvious that the invention hereinbefore described is extremely simple in its arrangement and construction and capable of accomplishing the desired result of automatically stopping a train in a very effective manner. 75

Having thus described my invention, what I claim as new is:

1. In a train stopping mechanism of the class described the combination of a tripping member arranged adjacent to the road bed, 80 a supporting base on which said tripping member is horizontally disposed, an operating rod connected to one end of said tripping member for shifting the same in a horizontal plane on the base, a valve operating arm carried by said tripping member and movable to and from an operative position by the operating rod, a spring mounted upon said base and arranged to exert pressure 85 against the end of said tripping member opposite the end carrying the valve operating arm, said spring being under tension when the tripping member is in inoperative position and adapted to facilitate the shifting of the tripping member by the operating means 90 upon actuation of the latter. 95

2. In a train stopping mechanism of the class described, the combination of a tripping member arranged adjacent to the road bed, an operating rod connected to the tripping member for actuation of the same to render it operative and inoperative, a spring coöoperating with the tripping member and adapted to be compressed upon actuation of the operating rod for moving the tripping member into inoperative position, said spring being arranged to throw said tripping member into operative position upon disablement of the operating rod aforesaid, and guide means for said spring comprising a rod around which the spring is arranged for maintaining the same in proper position when under compression. 105

3. In automatic train stopping mechanism of the class described, the combination of a tripping member arranged adjacent to the track and adapted to coöperate with a train valve, said tripping member being pivoted intermediate its length for movement in a horizontal plane, a valve contact arm bent upwardly from one end of said tripping member, an operating rod connected to the opposite end of said tripping member for shifting the same into operative and inoperative positions, and spring means co- 115 120 125 130

operating with the tripping member and adapted to be placed under tension upon shifting of the tripping member by the operating rod upon movement of said tripping member into inoperative position whereby to constitute auxiliary actuating means for said tripping member upon disablement of the operating means aforesaid.

In testimony whereof I affix my signature in presence of two witnesses.

CEZAIRE ^{his} X JOLY.
